UNITED STATES PATENT OFFICE.

CHARLES E. PATTBERG, OF NEW YORK, N. Y.

MECHANISM FOR PREVENTING OFFSET IN PRINTING-MACHINES.

SPECIFICATION forming part of Letters Patent No. 633,898, dated September 26, 1899.

Application filed January 29, 1897. Serial No. 621,147. (No model.)

To all whom it may concern:

Be it known that I, CHARLES E. PATTBERG, a citizen of the United States, residing at New York, in the county of New York and State of New York, have invented a new and useful Improvement in Attachments for Web-Printing Machines, of which the following is a specification.

The aim of this invention is to provide any of the forms of web-printing machines with an attachment or means whereby offset will be prevented and whereby the perfected web will be prevented from blurring as the same is drawn or led over the various rollers and mechanisms beyond the printing mechanism.

In my Patent No. 613,045, dated October 25, 1898, I have shown and claimed a device wherein an ink-drying medium, such as finely-powered talc or French chalk, may be deposited on the first printed side of the web in a web-printing machine before the web is led to the second impression-cylinder or printing mechanism, so as to prevent offset from the said second impression-cylinder.

In the present application I further carry out this invention by providing means whereby this offset-preventing medium will be applied to the second printed surface of the web and also preferably again to the first printed side of the web, so that the web passing over the subsequent rollers and folding mechanism will not have either side blurred.

I have found that by using a mixture of the character referred to not only will all the ink be kept on the web, but a highly-lustrous effect will be given thereto.

The ordinary offset-preventing device acts somewhat on the principle of a piece of blotting-paper, absorbing the surplus ink, thus rendering the letters or impression "cloudy," which of course is undesirable.

My invention works upon the opposite principle—that is, of keeping all the ink possible upon the work and setting or drying the ink by the drying medium which is applied thereto.

I will further describe my invention as applied to an ordinary form of rotary web-printing machine.

In the accompanying drawing I have shown in section how my invention may be applied thereto.

Referring to said drawing and in detail,

A designates the first printing-cylinder, B the first impression-cylinder, C the second impression-cylinder, and D the second printing-cylinder, of a web-printing press. The cylinders A and B print on one side of the web and form the parts I term the "first" printing mechanism, and the cylinders C and D print on the other side of the web and form the parts I term the "second" printing mechanism.

Coacting with the impression-cylinder A is a suitable inking device E, and coacting with the printing-cylinder D is a suitable inking device E'.

The web *w* is drawn from a web-roll W, being pulled therefrom by means of a drawing-in device, which consists of a continuously-rotating drum 10 and a set of tapes 13, which run around tape-pulleys 11, 12, and 14. From the drawing-in device the web passes between the cylinders A and B, then to the cylinder C, between the latter and the cylinder D, then around guiding-rollers 15 and 16, and between the rollers 17 and 18 to any suitable folding device, which is designated as F.

H represents a suitable hopper, in which are mounted a number of rollers, as 20 and 21, the last roller of which bears on the first impression-cylinder B. Powdered talc or chalk is placed in this hopper and is carried by the action of the rollers up to and deposited upon the first printed side of the web while the same lies upon the first impression-cylinder B.

22 represents a suitable casing in which is mounted a rotary brush 23, the purpose of which is to remove the surplus talc or chalk from the web before the same passes to the second impression-cylinder C.

28 designates another hopper, in which is mounted a roller 29 and in which the roller 15 is housed, and the roller 15 also serves to deposit talc immediately upon the side of the web which is last printed.

24 designates a suitable hopper in which are arranged rollers 26 and 27, the last roller 27 serving to deposit talc again on the first printed side of the web.

Rotary brushes, as 32 and 34, are arranged in suitable casings 31 and 33, so as to remove the surplus talc from the web as the same issues from between the rollers 15 and 27. Suit-

able knives or blades, as 19, may be arranged in the said hoppers to coöperate with the rollers 20, 26, and 29, and these blades may be provided with adjusting-screws 190, so that the amount of talc carried in can be regulated. The various rollers may be covered with any suitable medium which will convey talc—such, for example, as felt or soft rubber. By this construction it will be seen that the ink deposited upon the web by the plates on the cylinder A will have an immediate application of talc from the roller 21, so that set-off on the second impression-cylinder C will be substantially prevented. Also it will be seen that the second printed side of the web after the same emerges from between the cylinders C and D will immediately have talc or chalk deposited thereon before the same touches any roller or guide, so that the second printed side of the web will be immediately dried and prevented from being blurred or defaced in any manner as the web is drawn around the subsequent rollers and passed through the folding device.

25 I do not always use the hopper 24 and its rollers, but the same is desirable in many instances to insure the first printed side being perfectly dry before the web passes to the subsequent rollers and folding device. By this construction the printed product will be of a very high character.

30 The various rollers and parts herein shown are supposed to be driven by any of the usual forms of gearing which will be applied by the ordinary printing-press mechanic and need not be herein shown or detailed to give a clear understanding of my invention. The details and particular arrangements may also be varied as desired to suit the particular machine 35 to which my invention is applied.

Having thus fully described my invention, what I claim, and desire to secure by Letters Patent, is—

1. The combination with the first printing-cylinder and the first impression-cylinder and the second printing and impression cylinders of a tank and rollers arranged beneath the first impression-cylinder to apply an ink-drying substance to the web as it passes under the first impression-cylinder, a second set of rollers beneath the second impression-cylinder through which the web passes to the folding mechanism to be supplied with an ink-drying material after it receives the second impression, and adjustable blades acting on the lowermost of each set of rollers to regulate the amount of material carried thereby to the uppermost rollers all substantially as shown and described.

2. In a printing-machine, the combination of two impression-cylinders one upon each side of the web to be printed and means located on the same side of the web or sheet as the second impression-cylinder for applying an offset-preventing medium to the first printed surface of the sheet or web before the same reaches the second impression-cylinder and means located on the other side of the web or sheet for applying an offset-preventing medium to the second printed surface of the said sheet, substantially as and for the purpose specified.

In testimony whereof I have hereunto set my hand in the presence of two subscribing witnesses.

CHAS. E. PATTBERG.
